UNITED STATES PATENT OFFICE.

ALBERT L. IDE, OF SPRINGFIELD, ILLINOIS.

ENGINE-FRAME.

SPECIFICATION forming part of Letters Patent No. 396,209, dated January 15, 1889.

Application filed February 20, 1888. Serial No. 264,607. (No model.)

To all whom it may concern:

Be it known that I, ALBERT L. IDE, of Springfield, in the county of Sangamon and State of Illinois, have invented certain new and useful Improvements in Engine-Frames; and I do hereby declare that the following is a full, clear, and exact description thereof, reference being had to the accompanying drawings, and to the letters of reference marked thereon, which form a part of this specification.

This invention relates to improvements in steam, gas, and other engine-frames, and more particularly to frames for horizontal stationary engines of that class in which the frame is continuous and supports the cylinder at one end and is provided with crank-shaft bearings at its opposite end.

The invention consists in the matters hereinafter described, and pointed out in the appended claims.

In the accompanying drawings, Figure 1 is a perspective view of an engine and frame embodying my invention. Fig. 2 is a plan view of the frame. Fig. 3 is a longitudinal section of the engine-frame and operative parts therein. Fig. 4 is a cross-section of the engine-frame, taken upon line 4 4 of Fig. 3. Fig. 5 is a horizontal section of the frame, taken upon line 5 5 of Fig. 3. Fig. 6 is a detail cross-section of the frame, taken upon line 6 6 of Fig. 3.

As illustrated in said drawings, A is the engine-cylinder.

B is the frame; C, the crank-shaft; D, the piston-rod; E, the cross-head, and G, the connecting-rod. The crank-shaft is shown in the drawings as provided with two crank-disks, C' C'', to which is attached a crank-pin, C², engaging the connecting-rod G.

C³ is a fly-wheel upon the crank-shaft.

The cross-head E illustrated is like that shown in a prior patent, No. 321,727, dated July 7, 1885, and consists of a main part, E', of hollow or box form, and two bearing-plates, E² E³, secured to the top and bottom of the part E' and engaging the cross-head guides F F' of the frame.

E³ is a wrist-pin, which is secured in the opposite side walls of the hollow part E' of the cross-head and is engaged with the connecting-rod G.

The engine-frame is constructed as follows: Said frame is provided with a base, B', which is cast hollow and comprises two side walls, b' b', and a top wall, b², which latter forms the support for the lower cross-head guide, F'. The main or upper part of the frame, in its part B² adjacent to the cross-head guides, is provided with two side walls, B³ B³, which connect said cross-head guides at both sides thereof, so as to give a tubular form to said part B² of the frame. The said walls B³ B³ desirably form upward continuations of the side walls, b' b', of the frame-base B'. Within said hollow base are located cross ribs or flanges b³ b³, extending between the side walls, b' b', of the base and serving to support the wall b² and to give stiffness to the lower cross-head guide, F', formed upon said wall. The lower part of the base B' terminates in outwardly-extending horizontal flanges b⁴ b⁴, which rest upon the engine bed or foundation and through which suitable bolts are inserted for holding the frame in place. Said flanges extend the entire length of the frame from the cylinder to a point beneath the crank-shaft. At the end of the frame adjacent to the cylinder the tubular part B² is extended past the base B', so as to form a cylindric extension, b⁵, to which the cylinder is attached, the frame in this respect being like that shown and described in a prior patent, No. 314,381, granted to me March 24, 1885. Said cylindric part or extension b⁵ is herein shown as cast integral with the cylinder-head A', thereby rendering any separate head unnecessary.

The horizontal wall b², which forms the top wall of the hollow base B' and the bottom wall of the tubular part B², is extended from the end of the lower cross-head guide to form a wall, B⁴, which slopes downwardly to a point beneath the crank-disks and extends to the end of the frame. Said wall B⁴ in its part adjacent to and beneath the crank-shaft is located at the level of the bottom of the frame and joins at its side and end margins with the external base-flange, b¹, of the frame.

Each of the crank-shaft bearings b is supported by two inner and outer vertical walls, B⁵ B⁶, which form continuations of the side wall, B³, at the same side of the tubular part

B^2 of the frame, and which are joined at their upper margins and together form a hollow girder practically in alignment with the said side wall, B^3 . The said walls B^5 B^6 may be curved inwardly or brought together at their upper margins; but as herein shown they are connected by a flat horizontal top plate or wall, b^7 , which terminates in or is joined to the shaft-bearing b . At their lower parts the inner and outer side walls, B^5 B^6 , extend downwardly to the plate B^4 , which, at this point, forms the bottom of the frame. The inner and outer walls, B^5 B^6 , sustain the inner and outer parts of the crank-bearings, and form rigid and stiff girders, tending to hold the crank-bearings accurately in alignment with each other and to prevent yielding of the said bearings under whatever strain may be put upon them. The tubular main part B^2 of the frame, connected at one end directly with the cylinder, in connection with the parallel hollow girders formed by the walls B^5 B^6 , and forming continuations of said tubular part, form a frame of great stiffness and strength, and one which is at the same time of relatively little weight and contains a minimum quantity of metal.

B^7 is a transverse end wall, which extends across the lower part of the frame exterior to the crank-disks, and is connected with the walls B^5 B^6 by vertical side walls, B^8 B^9 , the rear or end margins of said walls B^5 B^6 being, in the particular construction illustrated, sloped or inclined outwardly and downwardly from the shaft-bearings to the bottom of the frame. The walls B^8 B^9 are triangular in form and fill the spaces between the side edges of the wall B^7 and the rear edges of the walls B^5 B^6 . Said walls B^5 B^6 and the walls B^7 and B^8 B^9 , together with the inclined wall B^4 , form a basin or tank, B^8 , which may be employed to contain a quantity of oil or other lubricant for the purpose of lubricating the several parts of the engine in the manner set forth in a separate application, Serial No. 264,608, filed by me in the United States Patent Office simultaneously herewith.

H is a hood or cover, which extends over the crank-disks and is fitted at its margins to the adjacent edges of the walls B^5 B^6 B^7 B^8 B^9 and to the adjacent edge b^8 , Fig. 3, of the tubular part B^2 of the frame. Said hood or cover, in connection with the adjacent parts of the frame constructed as above set forth, serves to entirely inclose the said crank-disks and connected operative parts, and thereby protects the same from dust and dirt, and at the same time confines the oil or lubricant and prevents the same from escaping to the exterior of the frame or being thrown outwardly upon surrounding objects.

In view of the advantages gained by the employment of such hood or cover in connection with a frame which is tubular near the cylinder, and is branched or forked to afford two bearings for the crank-shaft, a construction of this kind is herein claimed as new.

The construction illustrated, embracing the frame and hood made as above set forth, together with the cross-wall B^7 , forming the lower 70 part of a casing or housing surrounding the crank-disks, is also herein specifically claimed as a separate and further improvement.

I is a removable door, which is placed in one of the side walls, B^3 , of the tubular part 75 B^2 of the frame to afford access to the cross-head and guides when necessary for repairs or other purposes.

I claim as my invention—

1. An engine-frame constructed for the attachment of a cylinder at one end and having two shaft-bearings at its opposite end, said frame comprising a straight tubular part adjacent to the cylinder, constructed to support the cross-head guides and having two vertical 80 walls at each side of the frame, which form continuations of the side walls of the said tubular part, and which are connected with each other to form two hollow girders connecting the shaft-bearings with said tubular part of the 85 frame, substantially as described.

2. An engine-frame constructed for the attachment of a cylinder at one end and having two shaft-bearings at its opposite end, said frame comprising a straight tubular part adjacent to the cylinder, constructed to support the cross-head guides, a hollow base located beneath said tubular part, and two vertical 90 walls at each side of the frame, which are connected with each other to form hollow girders 95 continuous with the side walls of said tubular part, and which are constructed to support the shaft-bearings, substantially as described.

3. An engine-frame constructed for the attachment of a cylinder at one end and having two shaft-bearings at its opposite end, said frame comprising a straight tubular part adjacent to the cylinder, constructed to support the cross-head guides, a hollow base beneath 100 said tubular part, vertical side walls continuous with the side walls of the tubular part and supporting the shaft-bearings, and a bottom wall or plate, B^4 , extending downwardly from the lower wall of the tubular part to a point 105 beneath the crank-shaft bearings and connected at its side margins with the said vertical side walls, substantially as described.

4. An engine-frame comprising a cylindric part adjacent to the cylinder, a hollow base 110 beneath said cylindric part, two connected vertical walls at each side of the frame forming hollow girders continuous with the side walls of the said tubular part and supporting the shaft-bearings, and a bottom plate or wall, B^4 , 115 extending from the bottom of the tubular part to a point beneath the shaft-bearings and extending between and connecting the said vertical side walls, substantially as described.

5. The combination, with an engine-frame 120 provided with a tubular part adjacent to the cylinder and having vertical side walls forming continuations of the sides of said tubular part for supporting the shaft-bearings, and

having a bottom plate, B⁴, extending from the bottom wall of the tubular part between said vertical walls beneath the shaft-bearings, of a hood or cover fitted to the adjacent margins 5 of the said side walls, bottom plate, and tubular part for covering the crank-disks, substantially as described.

6. The combination, with an engine-frame comprising a tubular part adjacent to the cylinder, vertical side walls forming continuations of the tubular part for supporting the shaft-bearings, a bottom wall, B⁴, between said side walls, and a transverse wall, B⁷, connect-

ed at its side margins with the said side walls, of a cover or hood, H, fitted at its margins to 15 the said tubular part, the side walls, and the upper margin of the cross-wall B⁷, substantially as described.

In testimony that I claim the foregoing as my invention I affix my signature in presence 20 of two witnesses.
